DESIGN FOR A DUST MOP HEAD

Otto T. Schaefer, Detroit, Mich.

Application July 18, 1938, Serial No. 78,563

Term of patent 14 years

To all whom it may concern:

Be it known that I, Otto T. Schaefer, a citizen of the United States, residing at Detroit, county of Wayne, in the State of Michigan, have invented a new, original, and ornamental Design for A Dust Mop Head, of which the following is a specification, reference being made to the accompanying drawing, forming part thereof, in which:

Fig. 1 is a perspective view of a dust mop head, showing my new design.

Fig. 2 is a top plan view thereof. In Fig. 2 the strands are continued throughout the area represented by the broken lines.

I claim:

The ornamental design for a dust mop head, as shown and described.

OTTO T. SCHAEFER.
